UNITED STATES PATENT OFFICE.

LOUIS ROTH, OF ELIZABETH, NEW JERSEY, ASSIGNOR, BY MESNE ASSIGNMENTS, TO THE FRINK CORPORATION, OF NEW YORK, N. Y., A CORPORATION OF DELAWARE.

LIGHT FIXTURE FOR BEDS AND OTHER FURNITURE.

Application filed January 2, 1924. Serial No. 683,863.

This invention is a lighting fixture, and it pertains to a device adapted for use on articles of furniture such as beds, and in one embodiment the fixture is serviceable more particularly on folding beds.

A bed light requires easy application to a bedstead and provision for the protection of the electric current conductors and the incandescent lamp, which conductors and lamp are in general use at the present time. In addition to fulfilling the foregoing requirements, my new fixture performs additional function by making provision for changes in the position of the reflector hood to suit the convenience of the occupant, and for retaining said reflector hood in any one of several positions into which it may be shifted or adjusted. Furthermore, in one embodiment of the invention provision is made for an automatic adjustment of the fixture when used on or in conjunction with a folding bedstead of that type wherein the bedframe is raised or lowered with respect to the head board, so-called, such automatic adjustment affording the desired facility to the lighting fixture by permitting said fixture to turn out of the way of the bed frame upon moving the latter into a folded position relatively to the head board.

Other functions and advantages of the invention will appear from the following description taken in connection with the drawings, wherein—

Figure 1 is an end view of my lighting fixture applied to a bedrail.

Figure 2 is a plan view with parts in horizontal section.

Figure 3 is a detail view of a frictional retainer co-operable with the reflector hood for holding it frictionally in the required position.

Figure 4 is a plan view of another embodiment of the invention with parts in horizontal section illustrating means for mounting the fixture upon a folding bedstead in a manner to be shiftable automatically to the bedframe upon the movement of the latter to a folded position.

Figure 5 is an end elevation partly in section of the self adjusting fixture of Figure 4, the dotted lines illustrating the automatic movement of the fixture to accommodate itself to the folding movement of a bed frame.

Figures 6, 7 and 8 are views in side elevation, end elevation, and plan, respectively, of another embodiment of the invention, where-

in provision is made for mounting the hood and the lamp upon a desk, or other piece of furniture.

Referring to the structure disclosed in Figures 1 to 3, inclusive, A is a hood, B C are supporting members therefor, D a lamp socket and E an incandescent lamp.

The hood comprises a shell which is closed at the ends by heads α , α' , and open at α^2 on the under surface, said opening α^2 extending for substantially the length of the shell and being of appreciable width to emit the light rays downwardly. Obviously, the shell may be composed of material suitable for the purpose, such as metal. It is preferred to utilize the hood as a medium for reflecting the rays emanating from the electric lamp, and to this end the interior surface of said hood is polished, painted, or otherwise provided with such a light reflecting surface.

The hood as well as the lamp and the lamp socket are adapted to be mounted on a bedstead, or other article of furniture, by supporting means of simple and economical construction, and in one embodiment of the invention I provide said supporting means in the form of members B, C, one or both of which are tubular, as shown in Figure 2. Each member B or C consists of a pipe or tube which is straight for the major part of its length and is bent at substantially a right angle to produce a short arm b , said member being provided with male threads c , c' , one thread c at the end of the straight part and the other thread c' at the end of the short arm b .

The heads α , α' of the hood are provided with substantially central openings in which are received the short arms b of said members B C, and thus the hood is mounted on said members for rotative movement on an axis which extends longitudinally of the hood, the short arms b of the members B C serving the function of trunnions for the axial rotative movement of the hood. As shown, the trunnions or arms b are provided with collars d to arrest any tendency of the hood to slide lengthwise on the members, and the assemblage of the hood relatively to the trunnions or arms b is effected by screwing a nut d^2 on the threaded part c' of the arm on the member C, whereas the lamp socket D is screwed on the threaded part c' of the trunnion b on member B. The lamp socket D is of the form usual in the art, constructed

with a switch (not shown) operable by a pull chain D'. Said lamp socket is fixedly attached to the trunnion b of member B and is in coaxial relation to said trunnion so that any tendency of the lamp socket to shift out of the proper position is minimized. The lamp E is of the usual form, adapted to be screwed into the socket.

The socket D and lamp E are in fixed relation to the member B and to the hood so as to be encased substantially by said hood, but this hood is shiftable relatively to the lamp and the socket by rotating said hood on the axis afforded by the trunnions of the members B C. For retaining the loosely mounted hood in any one of the several positions into which it may be shifted, I employ frictional retaining means herein shown in the form of a spring washer or washers F F'. Each friction retainer is a single stamping of sheet metal, concavo-convex in cross section and provided with radial arms f and with a central opening, see Figure 3. The retainer F is fitted loosely on the trunnion b of member B, between the head a of the hood and the lamp socket D, whereas the other retainer F' is fitted loosely on the trunnion b of member C, intermediate the other head a' of the hood and the nut screwed thereon. The retainers are under tension by reason of the nut and the socket being screwed on the trunnions, and thus the retainers have such frictional contact with the heads of the hood as to hold said hood in position relative to the members B C, and at the same time permit the hood to be manipulated by hand so as to have the required rotative movement.

The supporting members B C are adapted for fixed attachment to the piece of furniture, and in the example shown, the threaded end portions c of said members B C are passed through openings provided in a rail G of a bedstead. The members are provided with collars g and on the threaded end portions c are screwed clamping nuts g' to draw the collars into tight engagement with the rail, washers g² being intermediate the rail and the nuts. Obviously, the bedrail G may be square, round or other form in cross section, and, in fact, the members B C may be attached fixedly to any article of furniture, or to any other place.

The fixture may be easily attached by inserting the members B C into holes provided in the supporting element, such as bedrail G, and one or both electric conductors E³ led through one of the tubular members, as B, to the lamp socket. The parts are quickly set up for service, and the entire device is simple in construction and economical of manufacture. The fixture is in a stationary relation to the bed except for the hood A which may be rotated on a horizontal axis to vary the relation of the light opening a² to the plane of the bed, whereby the light rays may be

thrown downwardly, forwardly or in any direction which the occupant may deem most convenient.

In Figures 4 and 5 of the drawings, there is illustrated another embodiment which includes means for frictionally holding a shiftable hood A' in position relatively to the stationary socket D² and a lamp E', all substantially as hereinbefore described, but in this form of the invention the fixture is shiftable bodily in order that the hood and the lamp with the socket may be moved bodily with respect to the article on which the fixture is mounted, as e. g. a folding bedstead including a stationary headboard G' and a swinging bedframe (not shown) movable on a horizontal axis.

The mount for the fixture includes supporting members B' C' and brackets H, H, each bracket being slotted at h to receive the end portion of one member, B' or C', whereby said members B' C' are attached pivotally to the brackets by the screws, pins or bolts i. The brackets rest upon the headboard G' and are attached fixedly thereto by screw bolts i'. The supporting members B' C' are free to swing on horizontal axis afforded by the pins i, but in the forward and downward movement of the hood and the lamp, the swinging motion of the members B' C' is arrested by stop lugs j contacting with the brackets H, H.

The supporting member C' is shown as being provided with a trunnion K on which is loosely fitted the head a' of the hood A', and with said trunnion and hood is associated a spring retainer F'. The supporting member B' is provided with a tubular trunnion k through which pass the leading in electric conductors to adapt the latter for attachment to the lamp socket D². Said tubular trunnion k is provided with a male thread on which is screwed the lamp socket in order to fixedly mount said socket on the tubular trunnion. The head a of the hood A' is fitted loosely on the tubular trunnion k, and a spring retainer F co-operates with said trunnion and with the hood. The retainers F F' have frictional engagement with the hood for retaining the same in the position into which said hood may be shifted.

The brackets H H are fixedly attached to the headboard G', but the supporting members B' C' have a movable relation to the headboard in order that the hood and the lamp may be turned into a position forwardly of said headboard and into overhanging relation to the bed. The lamp and hood are stationary in their forwardly extended positions, but the hood may be shifted by hand to reflect the rays of light in a desired direction. Upon an upward and rearward movement of the bedframe (not shown) to assume a folded position relatively to the headboard, the bedding carried by the folding bed frame impinges the hood A' and the fixture swings

bodily on the axis afforded by the pivots *i* and into the out of service position illustrated by dotted lines in Figure 4, whereby the fixture adjusts itself to the folding movement of the bedframe. The hood and lamp with the pivoted members *B' C'* swing to the off center position shown in dotted lines in Figure 4 so as to remain at rest and substantially free from contact with the bedding or the bed frame, but when the bedframe is lowered, it is necessary for the operator to swing the lamp fixture to the service position shown in full lines in Figure 4.

A still further embodiment of the invention is shown in Figures 6, 7 and 8, wherein provision is made for fixedly supporting the lamp and the hood upon a desk *I*, or other article of furniture. As shown, the mount includes a pedestal *J* provided with a foot member *j'* adapted to be fixedly attached to the rear angular corner of the desk, etc. Said pedestal carries a yoke-shaped supporting member *L*, the ends of which are provided with trunnions *M N* at least one of which is tubular for the reception of the leading in electric wires. As shown, the tubular trunnion *M* is provided with a collar *m*, a male thread *m'* and a socket *m²* into which is screwed a threaded end of the yoke *L*. The lamp socket *D³* is screwed on the male thread *m'*, and the head *a* of the hood *A²* is fitted loosely on the trunnion *M* so as to have contact with the collar *m*. Between the hood and the lamp socket is interposed the spring retainer *F* adapted for frictional contact with the hood and operating to hold said hood in the position to which it may be shifted. The other trunnion *N* is provided with a collar *n* and with two sockets, one of which is threaded. The end of the yoke is fitted in one of the sockets, and a screw *O* is threaded into the other socket for clamping the trunnion *N* into fixed relation to the yoke *L*, the head of said screw *O* holding a washer *o'* and a spring retainer similar to *F'* in the desired relation to the hood *A²*. The lamp *E²* is attached fixedly to the pull socket *D³*, whereas the hood *A²* is shiftable at will on the trunnions *M N*. As shown in Figure 7, the cross sectional contour of the hood may be modified to produce the forwardly extending member *a³*, whereby the area of the light opening *a²* is increased so as to direct the light rays over a wider area upon the desk top.

From the foregoing description taken in connection with the drawings, it will be noted that in each form illustrated the hood is normally stationary with respect to a lamp which is supported in position by a fixed socket, that said hood is shiftable by turning it on an axis extending lengthwise of the

hood, and that the retainer or retainers *F F'* have frictional contact with said hood for holding it in any one of several positions to 65 which the hood may be rotated by hand.

Having thus fully described the invention, what I claim as new and desire to secure by Letters Patent is:

1. In a bed lamp, supporting means 70 adapted to be fixedly attached to a bedframe, a plurality of arms each pivoted to said supporting means, a hood mounted on said arms for rotative movement, said hood and the arms being shiftable as a unit to an out of 75 service relation to a bedframe and also shiftable as a unit into a forwardly projecting service relation to said bed frame, means for arresting the movement of said swinging arms on the pivots when said arms and hood occupy the service positions and the out of service positions, and spring friction means co-operable with the arms and the hood for retaining said hood in adjusted positions with respect to the pivoted arms. 85

2. In a bed frame, supporting means adapted to be fixedly attached to a bedframe, a plurality of arms each pivoted to said supporting means, said arms being provided with trunnions, a hood fitted loosely 90 on said trunnions and coupling said arms to effect a conjoint movement of the hood and said arms, spring retainers fitted on the trunnions and confined in frictional engagement with said hood, said spring retainers being 95 under tension and contacting directly with the hood for holding the latter in position relatively to the arms, said hood and the pivoted arms being shiftable as a unit into an upstanding relation to the bed frame and being movable as a unit into a forwardly projecting relation to said bed frame, and means 100 on the pivoted arms and the supporting means for arresting the movement of the pivoted arms when shifted with the hood to the 105 upstanding position or to the forwardly projecting positions relatively to said bed frame.

3. In a bed lamp, a plurality of supporting arms provided with threaded trunnions, a hood fitted loosely on said trunnions, a collar 110 fixed on each trunnion and contacting with said hood, a lamp socket screwed on one trunnion, a nut screwed on the other trunnion, and a plurality of friction springs fitted 115 on the trunnions and held in position by the nut and the lamp socket respectively, said friction springs having direct frictional contact with said hood for retaining the latter in adjusted positions relatively to the supporting arms. 120

In testimony whereof I have hereto signed my name this 31 day of December, 1923.

LOUIS ROTH.
